(57) **CLAIM**

The ornamental design for a cutter head for cutting food products, as shown and described.

DESCRIPTION

FIG. 1 is a top perspective view of a cutter head for cutting food products showing our new design, in accordance with a first embodiment;

FIG. 2 is a bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top perspective view of a cutter head for cutting food products showing our new design, in accordance with a second embodiment;

FIG. 10 is a bottom perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a top perspective view of a cutter head for cutting food products showing our new design, in accordance with a third embodiment;

FIG. 18 is a bottom perspective view thereof;

FIG. 19 is a front elevation view thereof;

FIG. 20 is a rear elevation view thereof;

FIG. 21 is a left side elevation view thereof;

FIG. 22 is a right side elevation view thereof;

FIG. 23 is a top plan view thereof; and,

FIG. 24 is a bottom plan view thereof.

Portions of the cutter head for cutting food products illustrated in broken lines form no part of the claimed design.

1 Claim, 18 Drawing Sheets
